UNITED STATES PATENT OFFICE.

GEORGE C. WOLVEN, OF POUGHKEEPSIE, NEW YORK.

GAGE FOR PRINTING-PRESSES.

SPECIFICATION forming part of Letters Patent No. 662,047, dated November 20, 1900.

Application filed July 7, 1900. Serial No. 22,837. (No model.)

To all whom it may concern:

Be it known that I, GEORGE C. WOLVEN, a citizen of the United States, residing at Poughkeepsie, in the county of Dutchess and State of New York, have invented new and useful Improvements in Gages for Printing-Presses, of which the following is a specification.

My invention relates to improvements in adjustable guides or gages for use in platen printing-presses and embossing-machines.

One object of the invention is to provide an adjustable gage or guide which is simple and cheap of construction, capable of being easily applied and removed, and adjustable in any direction desired to secure an accurate register, and adapted to engage the tympan-paper firmly and securely, so as to effectually prevent slipping.

A further object of the invention is to provide a gage which may be adjusted without detaching it from the tympan-paper, which may be securely attached to a single sheet of tympan-paper and will not buckle or draw the paper, and which may also be used as an extension-guide and obviates the necessity of employing paste or lifting-clamps when attaching it to the tympan.

With these and other minor objects in view the invention consists of certain novel features of construction, combination, and arrangement of parts, as will be hereinafter more fully described, and particularly pointed out in the appended claims.

In the accompanying drawings, Figure 1 is a perspective view of a portion of a platen, showing the application of my improved gage thereto. Fig. 2 is a similar view of the platen with gage detached, showing the slit and slot formed in the tympan-sheet. Fig. 3 is a cross-section through the parts shown in Fig. 1. Fig. 4 is a side elevation of the gage. Fig. 5 is a bottom plan view of the body portion thereof. Fig. 6 is a perspective view showing a modification.

Referring now more particularly to the drawings, wherein like reference characters designate corresponding parts throughout the several views, the numeral 1 represents a portion of a platen of a printing-press or embossing-machine, and 2 one or more tympan-sheets applied thereto in any of the ordinary ways. It is a general custom to paste or ce-

ment a slug or similar device to the outer tympan-sheet to gage the position of the paper on the tympan. The position of such gage frequently has to be changed, tearing the paper 55 when removed and necessitating the substitution of a new paper, or, in lieu thereof, gage-pins, which perforate and are liable to slip and tear the paper, have been used. My 60 invention overcomes these and other objections.

The gage comprises two parts or members—namely, a gage proper and a clamp therefor. The gage proper is composed of a comparatively long and narrow plate 3, provided at one end with a head or stop 4, against which the paper on the tympan rests when in use, and at its opposite end with a downturned lip or flange 5. The head 4 extends transversely of and at an angle to the plate 3, and its bottom projects outwardly and downwardly, so that its forward edge 6 forms, like the lip or flange 5, a bearing point or portion to engage the paper and sustain the gage. 65 The plate 3 thus lies on a plane above parts 5 and 6, so that the gage has the general appearance of being bowed or curved upwardly and longitudinally with its ends in the same plane and its highest point at the center. 70 The outer or front face 8 of the head is thus also caused to lie at an angle to the plate 3, inclining outwardly and forwardly from its bearing point or edge 6, which is of advantage in preventing the edge of the paper on 75 the platen from slipping up and over upon the top of the gage, as will be readily understood. The plate 3 is formed with an opening 9 and a countersink 10 in its bottom around the said opening, as clearly shown in Fig. 5. The 80 clamping device for the gage consists of a head or button 11, provided with a screw shank or stem 12, extending upwardly through the opening 9, and a clamping-nut 13 applied to said shank or stem.

In the practical operation of my invention a comparatively long transverse slit 14 and intercommunicating slot 15, extending at right angles thereto, are formed in the tympan paper or sheet 2 at each point thereon at 85 which a gage is to be applied. In applying the gage the thumb-nut 13 is loosened and the head 11 inserted beneath the sheet 2 through the slit 14, so that the screw-shank 90

12 will occupy the slot 15 and the two bearing-points 5 and 6 of the plate 3 will bear upon the upper surface of the sheet. The gage is then adjusted to the proper position 5 along said slot and the thumb-nut 13 tightened up, whereupon the sheet 2 will be forced by the head 11 up into the countersink 10 and the bearing-points 5 and 6 will be caused to bear upon the upper surface of the sheet, 10 whereby the gage will be clamped to the sheet in such manner that no slipping of the gage can possibly occur. If after the gage has once been applied and tightened it is desired to adjust the same for accurately gag- 15 ing the same or a different sheet to be printed, this may be readily accomplished by simply loosening up the thumb-screw, sliding the gage along the slot to the desired extent, and then tightening up the nut, when the gage 20 will again be firmly clamped. Thus it will be seen that the gage may be quickly adjusted, applied, and removed by simply tightening and loosening the thumb-nut and without detaching any of the parts. The edge of 25 the paper to be printed or embossed rests against the outer inclined face 8 of the head 4, which by being outwardly, forwardly, and upwardly inclined to extend at an angle to the plate 3 effectually prevents the edge of 30 the paper from working upward. The points 5 and 6 are brought to bear firmly on the tympan-sheet without drawing or buckling the same, and the construction is such that the gage may be used also as an extension-guide, 35 if desired. The drawing of the tympan-sheet up into the countersink 10 obviously secures a firm connection and prevents slipping of the gage on the sheet. If desired, I may employ in connection with the gage an adjust- 40 able tongue 16, pivotally mounted to swing upon the shank 12 and clamped by the nut 13. This tongue has its outer or free end 17 bent upward and extending beyond the face 8 of the head 4 to guide the paper thereto. 45 The body portion of the tongue is provided with a straight front edge 18, forming a shoulder to abut against the rear face of the head and prevent casual displacement of the finger under pressure.

It will be seen from the foregoing descrip- 50 tion, taken in connection with the accompa-
nying drawings, that my invention provides
a gage which is simple of construction and
embodies important advantages due to its
novel features of construction alone, and it 55
will be understood that modifications within
the scope of the invention may be made with-
out departing from the spirit or sacrificing
any of the advantages thereof.

Having thus described my invention, what 60
I claim, and desire to secure by Letters Pat-
ent, is—

1. A feed-gage comprising a body having a countersink, and a clamp having a head to draw the platen-sheet into said countersink, 65 substantially as described.

2. A feed-gage comprising a plate having a countersunk opening, and a clamping device comprising a shank projecting through the opening, a head carried by the shank to draw 70 the platen-sheet into the countersink, and a nut on the shank, substantially as described.

3. A feed - gage comprising a generally curved or bowed gage member having end bearing-points to rest upon the tympan-sheet 75 and a central countersunk opening, and a clamping device comprising a head, a shank carrying the head and projecting through said opening, and a nut coöperating with said shank, substantially as described.

4. A feed - gage comprising a generally curved or bowed gage member having end bearing-points to rest upon the tympan-sheet and a central countersunk opening, a clamp- 85 ing device comprising a head, a shank carry-
ing the head and projecting through said open-
ing, and a nut coöperating with said shank,
and a tongue mounted on the shank and hav-
ing a square edge to bear against the stop of
the gage, substantially as described. 90

In testimony whereof I have hereunto set
my hand in the presence of two subscribing
witnesses.

GEORGE C. WOLVEN.
